by # UNITED STATES PATENT OFFICE.

GEORGE T. PILLINGS, OF BALTIMORE, MARYLAND.

SECTIONAL TUBULAR BOILER.

SPECIFICATION forming part of Letters Patent No. 276,873, dated May 1, 1883.
Application filed February 23, 1883. (No model.)

To all whom it may concern:

Be it known that I, GEORGE T. PILLINGS, of the city of Baltimore and State of Maryland, have invented certain Improvements in a Sectional Tubular Boiler, of which the following is a specification.

This invention relates to certain improvements in the construction of a sectional water tubular boiler, as hereinafter fully described.

10 In the accompanying drawings forming a part hereof, Figure I is a longitudinal section of the improved boiler. Fig. II is a transverse section of the same, taken on the dotted line *x x*, Fig. I. Figs. III and IV are views of parts of the invention on an enlarged scale.

15 Similar letters of reference indicate similar parts in all the views.

A. A are heaters, which consist of hollow castings of iron or steel, preferably of circular cross-section, and arched or curved longitudinally, as shown particularly in Fig. II. The heaters are provided with nozzles *a*, into which the lower ends of the vertical water-tubes *b* are screwed, and at their ends have transverse 25 openings *c*, surrounded by flanges *d*. On one side of the heaters the flanges *d* are tongued, and at the other side grooved, which admits of a series of them being firmly held together by bolts *e* and caps *f*. These heaters are connected to horizontal pipes *A'*, which extend longitudinally of the series of heaters, by pipes *A''*, which in diameter are about equal to the width of two of the tubes *b* and intervening space, as will be seen by referring to Fig. III.

30 35 The upper end of the vertical tubes *b* are united by tongued and grooved couplings *B*, which are held together by a bolt, *g*, and caps *H*, in a similar manner to the heaters A. I prefer to construct the boiler in two or more

40 45 main sections, each section consisting of an aggregation of vertical water-tubes with heaters and couplings, as described, the said main sections being united by offset pipes *C*, constructed to answer the purpose of caps *f*, and to give an increased length of water-tube, as shown in Fig. I. By this means mud or sediment is carried back from the first main section, under which fire is applied, to the rear ones, and thence to a mud-drum, *D*, by means 50 of a pipe, *E*.

The whole apparatus as described is in-

closed in walls *F* and slabs of fire-brick *G*, supported by bars, and the upper end of the water-tubes are united to drums or steam-receptacles *H*, which may be of any suitable 55 form.

The boiler is provided with grate-bars and furnace and other doors, and a bridge-wall, which require no description herein.

It will be understood that the heaters cannot be burned from accumulated mud, as their arched construction tends to conduct sediment to their ends, whence it passes to the rear end of the boiler, which is the lowest point thereof, and connected to the mud-drum. 60 65

The water-line is indicated by the dotted line *y y*, Fig. II.

Circulation of water in the boiler is effected by heat being applied directly under the tubes *b*, which causes the water therein to rise, the downward current being through the pipes *A''*, which are of larger area and somewhat protected from the fire by the walls *F*. (See Fig. II.) It will be seen that steam is taken from the upper end of all the vertical pipes and tubes. Consequently there is no tendency to the lifting of water or priming. 70 75

I claim as my invention—

1. In a sectional water tubular boiler, a series of arched heaters connected by vertical pipes to overhead horizontal pipes, which latter extend longitudinally of the said series of heaters, and a system of tubes of less cross area than the said pipes, secured at their lower end to the said heaters and at their upper 80 85 end united by couplings, the whole being in communication with a steam-drum through the medium of pipes leading from the said couplings or their connections, substantially as specified. 90

2. A sectional water tubular boiler constructed in sections, each one of which consists of heaters and vertical pipes and tubes connected at their upper end, as described, the said sections being united at their lower 95 end by offset pipes to give different lengths of water-tubes, substantially as and for the purpose specified.

GEORGE T. PILLINGS.
